To all whom it may concern:

Be it known that I, WALTER CAMP, of New Haven, in the county of New Haven and State of Connecticut, have invented a new Design 5 for the Ornamentation of Clock-Cases; and I do hereby declare the following, when taken in connection with accompanying drawing and the letters of reference marked thereon, to be a full, clear, and exact description of the 10 same, and which said drawing constitutes part of this specification and represents a face view.

This invention relates to a design for the ornamentation of clock-cases; and it consists 15 in the representation of a bell as the case of the clock, the frame and dial appearing on the front side of the bell, as shown in the accompanying illustration, and more fully hereinafter described.

20 The case represents a bell of that class commonly known as "church-bells," and is represented as standing upright, with the representation of the suspending-loops upon the top of the case as the crown.

Around the top of the case is the representation of a band with the representation of branches thereon, and around the bottom of the case is the representation of a similar band, also ornamented with branches. 25

On the front of the case is the representation of an ornamented panel extending from the band at the top to the band at the bottom, and in this panel is the dial, as shown in the accompanying illustration. 30

I claim—

The herein-described design for the ornamentation of clock-cases in the shape of a bell, having the representation of suspending-loops on the top as a crown and the representation of a band around the top and bottom, the said bands ornamented by branches, 40 as shown in the accompanying illustration.
